UNITED STATES PATENT OFFICE

162,643

TOWEL HOLDER OR SIMILAR ARTICLE

Myron Fox, Culver City, Calif.

Application July 1, 1950, Serial No. 10,919

Term of patent 3½ years

(Cl. D4—3)

To all whom it may concern:

Be it known that I, Myron Fox, a citizen of the United States, residing in Culver City, county of Los Angeles, State of California, have invented a new, original, and ornamental Design for Towel Holder or Similar Article, of which the following is a specification, reference being had to the accompanying drawing, forming part thereof.

I claim:

The ornamental design for a towel holder or similar article, substantially as shown.

MYRON FOX.
